UNITED STATES PATENT OFFICE.

SILAS M. FORD, OF ST. PAUL, MINNESOTA.

SHINGLE-STRIP.

1,207,523.

Specification of Letters Patent.

Patented Dec. 5, 1916.

Application filed March 11, 1916. Serial No. 83,505.

To all whom it may concern:

Be it known that I, SILAS M. FORD, a citizen of the United States, residing at St. Paul, in the county of Ramsey and State of Minnesota, have invented certain new and useful Improvements in Shingle-Strips, of which the following is a specification.

This invention relates mainly to shingle strips formed of water-proofed paper, felt 10 or material of a similar nature, which may or may not be covered with a mineral surfacing.

One object of my invention is to provide in a shingle strip having gutters, side walls 15 for the gutters projecting above the face of the shingle strip, to prevent water beating in laterally under the shingles along the gutter.

Another object of my invention is to provide in a shingle strip means for giving a 20 heavy appearance to the lower half of the shingle strip.

Another object of my invention is to provide in a shingle strip reinforcements for 25 the lower half of the shingle strip.

Another object of my invention is to provide in a shingle strip reinforcement in the lower half of the shingle strip that will butt 30 against the lower edge of the next shingle strip above, thus stiffening the lower half of the shingle strip against the lifting of the wind.

With these and incidental objects in view the invention consists of certain novel features 35 of construction and combination of parts, the essential elements of which are hereinafter described with reference to the drawing which accompanies and forms a part of this specification.

In the drawing Figure 1 is a plan view of 40 two shingle strips embodying my invention, one superimposed upon the other. Fig. 2 is a front elevation of the two shingle strips shown in Fig. 1, while Fig. 3 is a section 45 taken on the line A A, Fig. 1, and Fig. 4 is a perspective view of a strip of roofing material showing the development of the shingle strips shown in Figs. 1 and 2.

The strip of roofing material 1, Fig. 4, 50 is sheared along the lines 2 and 3 at equal distances throughout the strip, the surfacing material with which the remainder of the strip is covered having been removed or omitted on the surface between the lines 3, 55 4 and 5.

The underside of the shingle strip is pref-

arably scored along the lines 4 and 5 back to the line 3 at each point where the gutters are to be formed, allowing the material of the folds 6 and 7 to be bent upwardly at 60 right angles, and then bent down squarely against the surface of the strip at 8 and 9, the tackiness of the water-proofing material in the strip securely binding the folds 6 and 7 squarely to the upper surface of the shingle strip.

The folds 6 and 7 as they are shown at 8 and 9, and also shown in Figs. 1 and 2 in the completed shingle strip serve as longitudinal 70 reinforcements for the lower half of the shingle strip, and as in mineral surfaced shingles the upper surface of these folds would be black, while the gutter would show the color of the mineral surface of the shingle strip below, the result is a heavy pleasing effect 75 when laid upon a roof in shingle fashion.

The shoulders formed by the folds at 3 serve as a guide for laying the shingle strip above, and as these are raised above the surface of the shingle strip no care is needed to align shingle strips of this construction, as they will naturally seat themselves against the shoulders at the point 3. Furthermore, as the shoulders 3 of the folds butt tightly 80 against the lower edge of the shingle strip above, the reinforcement produced by the folds is extended to the lower edge of the shingle strip above, and hence the lower half 85 of the shingle strip is strengthened throughout against being lifted by the wind. 90

As the strips are laid upon a roof in shingle fashion, it is evident that any water that is blown diagonally or transversely across the roof will be dammed up by the folds constituting the reinforcement, and not blown into the gutter, and as the reinforcement is higher than the surface a certain amount of protection is also afforded 95 against the beating of the rain into the gutter, hence there is less possibility for rain to be driven under shingles of this type than of other types. 100

While I have described my invention and illustrated it in one particular design, I do not wish it understood that I limit myself to this construction, as it is evident that the application of my invention may be varied in many ways within the scope of the following claims. 105

Claims:

1. A roofing strip having shingle-like tabs formed throughout the lower portion there-

- of, the side edges of said tabs being thickened to reinforce the tab, and forming a channel or gutter between the thickened portions.
5. 2. A roofing strip having shingle-like tabs formed throughout the lower portion thereof by a T shaped slit, the side edges of the tabs being reinforced by bending the portions described by the slitting, back upon the tab.
- 10 3. A roofing strip having shingle-like tabs formed throughout the lower portion thereof by a T shaped slit, the side edges of the
- tabs being reinforced by bending the portions described by the slitting, back upon the upper surface of the tab forming a gutter, and the upper end of said turned back portion forming a gage line for laying the superimposed strip.
4. As an article of manufacture a roofing strip having shingle-like tabs formed throughout the lower portion thereof, and reinforcing means extending along the side edges of said tabs so formed.

SILAS M. FORD.
